BURNER NOZZLE

Morris O. Wise, South Bend, Ind., assignor to
 Bendix Aviation Corporation, South Bend, Ind.,
 a corporation of Delaware

Application May 15, 1947, Serial No. 748,214

4 Claims. (Cl. 299—118)

1

This invention relates to burner nozzles; it is particularly concerned with nozzles for supplying fuel to the burner system of a gas turbine engine at a substantially constant pressure. In such systems there may be a relatively large number of nozzles receiving fuel under pressure from a common fuel manifold, and discharging the fuel into a series of burners individual to the respective nozzles or a single burner common to all nozzles; and it is important that the nozzles remain closed with a minimum of leakage or "drip" until the manifold pressure attains a predetermined or given value, and then open and effectively discharge the fuel in the form of a fine conical spray; and the primary object of the invention is to provide a nozzle which will effectively meet such requirements.

Another object is to provide a burner nozzle which will produce atomization and a well rounded spray over a wide range of pressures even though at the beginning of the range the pressure is at a relatively low value.

A further object is to provide a nozzle of the type specified which is reliable in operation and of relatively simple construction.

The foregoing and other objects and advantages will become apparent in view of the following description taken in conjunction with the drawings, wherein:

Figure 1 is a substantially central longitudinal sectional view taken through a nozzle embodying the invention;

Figures 2 and 3 are cross sections taken substantially on the lines 2—2 and 3—3, Figure 1;

Figure 4 is a view in side elevation of the complete nozzle; and

Figure 5 is a central longitudinal section of a modified form of nozzle member.

Referring to the drawings in detail, 10 indicates the nozzle body which is hollow and defines an elongated fuel chamber 10', said body being formed with an external hex flange 11 and at one end has a reduced externally and internally screw threaded mounting shank 12. At its discharge end, the nozzle body is preferably recessed as at 13 and formed with an internal flange 14. Mounted within the hollow central portion of the nozzle body is a nozzle member 15 having a nozzle tip 15' and a central spin chamber 16 terminated in an axial fuel discharge passage or opening 17. A series of cross ducts 18 serve, when open, to communicate the fuel chamber 10' with the spin chamber 16, said ducts projecting at a tangent to the spin chamber 16 so that as the fuel enters this chamber under pressure, it will have im-

parted thereto a whirling action which will produce a fine conical discharge spray from the opening 17.

Overlying the spin chamber is a closure member 19 which may be secured in place by having the surrounding metal peened thereover. The nozzle member 15 also has a hollow inner end wall 20 defining a chamber 20' in which is mounted a spring 21, the chamber 20' being vented to the spin chamber 16 by means of a hole or opening 22 formed in the closure member 19.

A flange 23, formed on the periphery of the nozzle member 15, is adapted to abut the flange 14 formed on the body member 10 and determine the location of the said nozzle member when the latter is press-fitted in the opening defined by the said flange. The peripheral surface of the wall 20 is preferably formed with one or more annular recesses 24, to catch foreign matter or abrasive particles and to facilitate a smooth sliding action between said surface and a piston type valve 25.

The nozzle member 15 is of a diameter such that when it is inserted in the fuel chamber 10' there is sufficient clearance to permit the piston valve 25 to be telescoped thereover and still leave a space for fuel in the chamber 10', said piston 25 having a skirt 26 formed with a series of ports 27 which feed into an annular channel 28. When the channel 28 is in register with the ducts 18, fuel may flow into the whirl chamber 16 and thence be discharged through the tip opening 17.

A cap 29 is threaded into the end of the body 10 and is formed with a passage 30 and a chamber 31 in which is mounted a check valve in the form of a ball 32 urged towards seated position by a spring 33.

To produce a relatively wide or full spray at pressures even as low as drip or leak pressures, one or more fine cross vents or bleeds 34 are formed in the nozzle member and communicate the fuel chamber 10' with the spin chamber 16 beyond the skirt 26 of the piston 25, said vents or bleeds being arranged at a tangent to the said spin chamber in the same manner as the passages 18.

In operation, fuel under pressure from a fuel manifold or the like, not shown, enters at 30 and unseats the ball check valve 32 at a pressure of say, for example, twenty p. s. i. When the pressure of the fuel attains a value of, for example, ninety p. s. i. it depresses the piston 25 against the resistance of the spring 21, and when the annular channel 28 registers with the tangential ducts 18, fuel flows under pressure from the fuel

chamber 18' into the swirl chamber 16 and is discharged from the nozzle opening 17 in the form of a fine swirling spray or cone.

When the manifold pressure drops below a predetermined value (ninety p. s. i. in the present instance) the piston 25 retracts due to the force exerted by the spring 21, the annular channel 28 moving out of registration with the tangential ports 18 and closing off flow of fuel to the swirl chamber 18.

The small cross vents or bleeds 34 communicate fuel under pressure to the spin chamber as soon as the check valve opens, and if there is any leakage fuel flowing from the chamber 20' into the spin chamber at this time, it is caught in the swirl and diffused in a fine conical spray as it issues from the nozzle opening. There is thus substantially no "drip" from the nozzle. Also, if desired, the check valve can be set to open at very low pressures and produce an initial fine starting discharge spray before the piston valve 25 opens and the full, substantially constant pressure discharge takes place.

The piston 25 will remain open as long as the fuel pressure remains at a given value and the discharge spray cone will remain full at all pressures sufficient to cause discharge from the nozzle. When the nozzle closes, there is relatively little leakage or "drip" from the discharge opening 17. By venting the leakage fuel to the spin chamber or nozzle tip, no sealing bellows is necessary as in certain other types of nozzles. The nozzle assembly is relatively simple and can be made at a relatively low cost in view of the exactitude required of burner nozzles for gas turbine burner systems.

In Figure 5 the nozzle member, indicated at 35, is generally similar to the nozzle member 15 of the preceding figures except in this instance the chamber 36, which corresponds to the chamber 20' of Figure 1, is vented directly to the nozzle tip by way of longitudinal passages 37 instead of being vented to the spin chamber 16, the latter being closed by a member 38 corresponding to the member 19 of Figure 1, except that it lacks the opening 22. Parts which conform exactly to those of the nozzle member of Figure 1 are given similar reference numerals. This type of nozzle member may prove desirable in certain instances, but it lacks the low pressure spin feature of the nozzle member 15.

It will be understood that certain minor changes in construction and design may be adopted without departing from the scope of the invention as defined by the appended claims.

I claim:

1. A burner nozzle comprising a nozzle body formed with a fuel chamber adapted to receive fuel under pressure, a nozzle member fixed in said fuel chamber and formed with a nozzle tip and a spin chamber terminating in a fuel discharge opening substantially centrally of said tip, the nozzle member being also formed with one or more fuel ducts or passages disposed at a tangent to said spin chamber for conducting fuel from said fuel chamber to said spin chamber, a valve in the form of a hollow piston telescoped over said nozzle member and having a skirt portion coacting with said ducts, said piston valve tending to move in a direction to open said ducts when subjected to the pressure of fuel in said fuel chamber, a spring interposed between said nozzle member and said piston, said spring normally urging the piston valve towards closed position and maintaining the valve closed at fuel pressures below

a predetermined value, means venting the chamber formed by said piston valve and said nozzle member to the spin chamber, said nozzle member being formed with one or more additional tangential fuel ducts of smaller diameter or flow capacity than said first named fuel ducts communicating the fuel chamber with the spin chamber for admitting fuel to said spin chamber at fuel pressures below those required to open said piston valve.

2. A burner nozzle comprising a nozzle body formed with a fuel chamber and a flow passage through which fuel flows under pressure to said chamber, a nozzle member fixed in said fuel chamber and formed with a nozzle tip and a fuel discharge opening substantially axially of said tip, the nozzle member being also formed with one or more fuel ducts or passages for conducting fuel from said fuel chamber to said discharge opening, a piston type valve arranged in sliding telescoping relation to said nozzle member for controlling admission of fuel from said fuel chamber through said ducts to said discharge opening, said piston valve tending to move in a direction to pass fuel to said discharge opening when subjected to the pressure of fuel in said fuel chamber, a spring normally urging said valve towards closed position and maintaining the valve closed at fuel pressure below a predetermined value, a check valve disposed in said flow passage leading to the fuel chamber, said check valve being adapted to remain closed at fuel pressures below a predetermined value and to open at a pressure lower than that required to open said piston valve and pass fuel to said fuel chamber, and passage means for conducting low pressure fuel from said latter chamber to said fuel discharge opening when said piston valve is closed and said check valve is open.

3. A burner nozzle comprising a nozzle body formed with an elongated fuel chamber having a flow passage for the intake of fuel at one end of said chamber and a mounting flange at the opposite end of said chamber, a nozzle member adapted to be inserted in said chamber and held in fixed position by said flange, said nozzle member having a hollow skirt portion and a spin chamber terminating in a fuel discharge opening substantially axially of the nozzle tip, said nozzle member being also formed with fuel ducts for communicating fuel under pressure from said fuel chamber to said spin chamber, said ducts being disposed at a tangent to said spin chamber to cause the fuel to whirl in said latter chamber, a valve member in the form of a hollow piston telescoped over the skirt portion of said nozzle member and provided with fuel inlet ports leading to an annular passage adapted to register with said ducts when the valve member is subjected to fuel under predetermined pressure, a spring disposed in the skirt portion of said nozzle member and engaging said piston, said spring maintaining the piston valve closed at pressures below a predetermined value, and one or more vent passages venting the interior of said nozzle member past the spin chamber to a point adjacent said discharge opening.

4. A burner nozzle comprising a nozzle body formed with a fuel chamber adapted to receive fuel under pressure, a nozzle member fixed in said fuel chamber and provided with a nozzle tip having a spin chamber and a fuel discharge opening, said nozzle member being provided with one or more tangential passages for communicating fuel under pressure from the fuel chamber to the spin

chamber, a piston valve coacting with said nozzle member and arranged in sliding telescoping relation to said nozzle member for controlling admission of fuel to said spin chamber, said piston valve tending to move in a direction to pass fuel to said discharge opening when subjected to the pressure of fuel in said fuel chamber, a spring normally urging said valve towards closed position and maintaining the valve closed at fuel pressures below a predetermined value, and a check valve controlling flow of fuel into said fuel chamber, said check valve being adapted to close at fuel pressures below a predetermined value and close off flow of fuel to said fuel chamber, said nozzle member being formed with additional tangential 10 passages communicating the fuel chamber with

the spin chamber beyond said piston valve for admitting fuel to the spin chamber when the check valve opens and before the piston valve opens.
